CLAIM

The ornamental design for a support stake, as shown and described.

DESCRIPTION

FIG. 1 is the top view of the support stake of the present invention.

FIG. 2 is the bottom view of the support stake of the present invention.

FIG. 3 is the rear view of the support stake of the present invention.

FIG. 4 is an elevation view of the support stake of the present invention.

FIG. 5 is the front view of the support stake of the present invention.

FIG. 6 is the elevation view of the support stake of the present invention, opposite to the view seen in FIG. 4.

FIG. 7 is a perspective view of the support stake of the present invention.

FIG. 8 is a view of the support stake of the present invention in a use context.

FIG. 9 is another view of the support stake of the present invention in a use context; and,

FIG. 10 is another view of the support stake of the present invention in a use context.

The broken lines in FIGS. 8-10 depict environment and form no part in the claimed design.
